CONVEYER AND ROTARY DRUM THEREFOR

William A. Frank, Jersey City, N. J.

Application September 30, 1936, Serial No. 103,238

7 Claims. (Cl. 214—17)

My invention relates to a combination continuous conveyer and automatic agitator and dumper and has for its object to provide a continuous conveyer operating within a suitable frame work 5 and enclosure and being provided with a plurality of especially constructed rotatable agitator and dumper units, which are arranged at spaced intervals along the length of the conveyer, and which are adapted to receive and retain charges 10 of material to be processed while being conveyed from one station to another and especially while the units are being revolved in one direction, and to dump or discharge their loads when subjected to rotation in the reverse direction.

15 I accomplish this object by means of arrangement and combination of parts hereinafter described, set forth in the appended claims and illustratively exemplified in the accompanying drawings, in which,

20 Figure 1 is a side elevational view of the supporting structure, conveyer and rotatably mounted agitator and dumper units carried by the conveyer;

25 Figure 2 is a perspective view of an agitator and dumper unit showing the means used to rotate the same in one or the other direction;

Figure 3 is a substantially transverse sectional view of a unit taken on lines 3—3 of Figure 2.

Referring to the drawings, 10 denotes the side frame structure of a device for processing certain materials, the frame being provided with a superstructure 11 at its uppermost portion and suitably disposed tanks 12 arranged in the lower section. A plurality of stud shafts 13 are supported 35 in bearings 14 arranged transversely of the frame 10 and each shaft carries one of a pair of spaced sprockets 15, one set of sprockets being disposed adjacent the bottom of each tank 12. Supported 40 on the sprockets on each side of the device is a continuous sprocket chain 16, the two chains thus mounted forming a continuous conveyer movable through the superstructure 11, frame structure 10 and tanks 12.

45 A plurality of agitator and dumper units 17 are carried at spaced intervals transversely of the conveyer chains 16 on pins 18, which project towards each other and are mounted on the inner sides of certain of the chain links, the pins being coaxially aligned whenever they occur in the conveyer.

Each agitator and dumper unit 17 comprises 50 a drum having end plates or heads 19 to which are secured the ends of a spiral sheet metal portion 20, which forms the sides and inner part of the drum. The sides 20 consist preferably of a

series of parallel plates angularly disposed with respect to each other to form a spiral in which the parallel longitudinal end plates overlap to provide an opening 21 into the interior of the drum.

5 The heads 19 are provided with bearing members to receive the chain pins 18 so as to allow the drum to revolve freely about its longitudinal axis between the chains 16 of the conveyer.

Rotary motion is imparted to each drum 17 by means of a sprocket or gear 22 carried by 10 one of the heads 19 and adapted to move into engagement with a fixed chain or rack 23 mounted in the frame 10, superstructure 11, or tanks 12 at one or the other side of the path traversed 15 by the conveyer. In the present instance, the chain or rack 23 follows the path of the conveyer through the tanks 12 so as to cause the drum to revolve in a counterclockwise direction and the contents to be tumbled, mixed or otherwise 20 agitated in any desired bath or atmosphere within the tanks. Suitable racks 23 may be placed anywhere along the conveyer to cause rotation of the drum in carrying out any desired process. However, when the drum is to be loaded or discharged its direction of rotation must be 25 reversed and this is brought about in the present embodiment by the chain or rack 23a arranged in the superstructure 11, the rack 23a being disposed on the opposite side of the path of travel of the 30 conveyer from that occupied by the chain or rack 23.

In operation, let it be assumed that the conveyer 16 and its drums 17 are moving from left to right along the upper strand and that a drum 35 has received its charge through the opening 21. The drum and conveyer turn about the sprockets 15 and descend into the first tank 12 and in its downward path of movement the sprocket or gear 22 engages the chain or rack 23 and causes the 40 drum to rotate in a counterclockwise direction, as indicated by the arrow in Figure 1, whereby the contents are tumbled about but are retained within the drum. This operation may continue for any distance throughout the path of the conveyer or it may be intermittently carried on depending of course upon the nature of the 45 processing. When the drums are to be rotated in the reverse direction for the purpose of discharging their contents the chain or rack 23a is engaged by the sprocket or gear 22. In the present case the rack 23a is arranged in the superstructure 11 so as to cause the drum to dump at this point.

In the drawings, only three drums are shown. 55

but it will be understood that any suitable number may be attached to the conveyer.

The chains 16 of the conveyer traversing the spaces between supporting sprockets 15 require 5 guiding means 24, which is in the form of a channel rod mounted on the frame on each side thereof and adapted to embrace the chain 16 of the conveyer. This arrangement is particularly desirable in the vertical movement of the conveyer 10 along sections where the drums are required to rotate and agitate the contents and their sprockets or gears 22 must be held in mesh with the fixed chains or racks 23.

Having described my invention and the manner in which the same operates, what I claim and desire to secure by Letters Patent is:

1. A conveyer arrangement comprising endless parallel chains, a plurality of drums rotatably mounted between and carried at spaced intervals by said chains each drum comprising head plates and side plates arranged at angles to each other to form a spiral in transverse section, the ends of the sides overlapping to form a longitudinal opening so as to permit the contents to remain within the drum when the latter is rotated in one direction and to cause the contents to be discharged through the opening when the drum is rotated in a reverse direction, a pinion attached to each drum, a stationary rack arranged 25 along a predetermined portion of the path traversed by said pinions, said rack being positioned on one side of said path to be engaged by said pinions, when they pass said portion of the path, thereby rotating the pinions and drums in 30 said first mentioned direction without discharge of the contents, and a second stationary rack arranged along a subsequent portion of the path of the pinions and being positioned on the opposite side of said path to be engaged by said pinions as they reach such subsequent portion of the path, whereupon the rotation of the drums is reversed for the discharge of the contents.

2. A combination, as claimed in claim 1, including sprocket wheels supporting the conveyer 45 chains at the turns in its direction of travel and a frame to support said wheels and to carry the racks to be engaged by the pinions of the drums.

3. A combination, as claimed in claim 1, including sprocket wheels supporting the conveyer 50 chains at the turns in its direction of travel, a frame to support said wheels and to carry the fixed racks alongside the path of said pinions, and tanks arranged in the frame and adapted to embrace certain of the sprocket wheels to carry the conveyer into the tanks, said first mentioned rack being provided along a portion of the path of the pinions including at least part of the path through said tank and said second rack being 55 positioned along a portion of said pinion path outside of said tank.

4. A combination, as claimed in claim 1, including sprocket wheels supporting the conveyer 60 chains at the turns in its direction of travel, a frame to support said wheels and to carry the fixed racks alongside the path of said pinions, tanks arranged in the frame and adapted to embrace certain of the sprocket wheels to carry the conveyer into the tanks and guide members 65

in which the conveyer chains run in their substantially vertical travel into and out of the tanks, said first mentioned rack being provided along a portion of the path of the pinions including at least part of the path through said tank and said second rack being positioned along a portion of the pinion path outside of said tank. 5

5. Conveyer arrangement comprising an endless chain, a rotatable drum having an opening 10 therein and a spiral wall overlapping said opening whereby the contents remain within the drum when the latter is rotated in one direction and are discharged through the opening when the drum is rotated in the reverse direction, said drum being carried on said conveyer chain free for rotation in both said directions, a circular toothed member rigidly fixed to said drum coaxial with the axis of rotation of the latter, a stationary control means arranged along a predetermined portion of the path traversed by said 15 drum and positioned on one side of said path to be engaged by said toothed member when the drum passes said portion of its path, whereby said toothed member and drum are rotated in said first mentioned direction without discharge 20 of the drum contents, and a second stationary control means arranged along a subsequent portion of said drum path on the opposite side thereof in a position to be engaged by said toothed member when the drum has reached said subsequent portion of its path, whereupon the rotation 25 of the drum is reversed for discharge of the contents. 30

6. Conveyer arrangement comprising an endless chain, a rotatable drum having an opening 35 therein and a spiral wall overlapping said opening, whereby the contents remain within the drum when the latter is rotated in one direction and are discharged through the opening when the drum is rotated in the reverse direction, said drum being carried on said conveyer chain free for rotation in both said directions, a circular toothed member fixed to said drum coaxial with the axis of rotation of the latter, a tank arranged 40 to enclose part of said conveyer chain, a stationary control means arranged along a predetermined portion of the path traversed by said drum including at least a part of the path through the tank, said control means being positioned on one side of said path to be engaged by said toothed member, when the drum passes said predetermined portion of its path whereby said toothed member and drum are rotated in said first mentioned direction without discharge 45 of the drum contents, and a second stationary control means arranged along a subsequent portion of said drum path outside said tank, said second means being positioned on the opposite side of said drum path to be engaged by said toothed member, when the drum has reached said subsequent portion of its path, whereupon the rotation 50 of the drum is reversed for discharge of the contents. 55

7. An arrangement, as claimed in claim 5, in which said circular toothed member consists of a pinion and said control means comprise racks arranged along subsequent portions and at opposite sides of the path traversed by said pinion. 60
